UNITED STATES PATENT OFFICE.

CELESTINA MASCONI, OF BROOKLYN, NEW YORK, ASSIGNOR TO E. GREENFIELD'S SONS, OF BROOKLYN, NEW YORK, A CORPORATION OF NEW YORK.

DESIGN FOR A CANDY OR SIMILAR ARTICLE OF MANUFACTURE.

59,760.

Specification for Design.

Patented Nov. 22, 1921.

Application filed March 31, 1921. Serial No. 457,525. Term of patent 14 years.

To all whom it may concern:

Be it known that I, CELESTINA MASCONI, of the city and State of New York, have invented a new, original, and ornamental Design for a Candy or Similar Article of Manufacture, of which the following is a specification, reference being had to the drawing, forming a part thereof.

In the drawing, Figure 1 shows a top view of the candy or similar article of manufacture,

Fig. 2 is an end view, and
Fig. 3 is a front elevation.

I claim:—

The ornamental design for a candy or similar article of manufacture substantially as shown.

CELESTINA MASCONI.
